(57) **CLAIM**

The ornamental design for the reading pillow as shown and described.

DESCRIPTION

FIG. 1 is a perspective view of a reading pillow showing the design;

FIG. 2 is a second perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof; and,

FIG. 8 is a right elevation view thereof.

Dashed broken lines in the drawings depict portions of the reading pillow that form no part of the claimed design.
